BICYCLE REFLECTOR

Nicholas A. Amoroso, Hillsdale, N.J., assignor to
Bright Star Industries, Clifton, N.J.

Original design application Mar. 27, 1974, Ser. No.
455,133. Divided and this application Feb. 5, 1975,
Ser. No. 547,364

Term of patent 14 years

Int. Cl. D10—06

U.S. Cl. D10—111

FIG. 1

FIG. 2

FIG. 3

FIG. 4

FIG. 5

FIG. 1 is a front isometric view of a bicycle reflector of the present invention;

FIG. 2 is a rear isometric view of the bicycle reflector of the present invention;

FIG. 3 is a side elevation view of the bicycle reflector of the present invention;

FIG. 4 is a top elevation view of the bicycle reflector of the present invention; and

FIG. 5 is a bottom elevation view of the bicycle reflector of the present invention.

The cross-hatching indicating faceting is partially shown on the reflector for convenience of illustration, it being understood that the cross-hatching is uniformly continuous over the areas indicated.

This is a division of design application Ser. No. 455,133, filed Mar. 27, 1974.

I claim:

The ornamental design for a bicycle reflector, substantially as shown.
